ADVERTISING DISPLAY

Nicholas Karos, Skokie, Ill.

Application May 21, 1957, Serial No. 46,259

Term of patent 14 years

(Cl. D1—12)

Fig. 1 is a front elevational view of an advertising display showing my new design, the rear of the disc being substantially plain and a portion of the standard being broken away to indicate indeterminate length; and

Fig. 2 is a side elevational view taken from the left of Fig. 1, part of the upright being broken away for convenience of illustration.

The dominant features of my design reside in the full line portions of the drawing.

I claim:

The original design for an advertising display, substantially as shown and described.
